(57) **CLAIM**

The ornamental design for a side rail, as shown and described.

DESCRIPTION

Cross reference is made to U.S. patent application Ser. No. 29/436,400 entitled "Bed Frame" by Richard H. Heimbrock, which was filed on Nov. 5, 2012 and is hereby incorporated herein by reference.

FIG. 1 is a front perspective view of one embodiment of a side rail showing our new design;

FIG. 2 is a rear perspective view of the side rail of FIG. 1;

FIG. 3 is a first side elevation view of the side rail of FIG. 1; FIG. 4 is a second side elevation view of the side rail of FIG. 1;

FIG. 5 is a top plan view of the side rail of FIG. 1;

FIG. 6 is a bottom plan view of the side rail of FIG. 1;

FIG. 7 is a rear elevation view of the side rail of FIG. 1;

FIG. 8 is a front elevation view of the side rail of FIG. 1;

FIG. 9 is a front perspective view of another embodiment of the side rail showing our new design;

FIG. 10 is a rear perspective view of the side rail of FIG. 9;

FIG. 11 is a first side elevation view of the side rail of FIG. 9; FIG. 12 is a second side elevation view of the side rail of FIG. 9;

FIG. 13 is a top plan view of the side rail of FIG. 9;

FIG. 14 is a bottom plan view of the side rail of FIG. 9;

FIG. 15 is a rear elevation view of the side rail of FIG. 9; and, FIG. 16 is a front elevation view of the side rail of FIG. 9.

The broken lines shown in the figures depict environmental subject matter and form no part of the claimed design. The solid black surface shading indicates a contrasting appearance.

1 Claim, 12 Drawing Sheets
